UNITED STATES PATENT OFFICE.

FRANK B. TAFF, OF WHITESTONE LANDING, NEW YORK.

PROPELLING MECHANISM.

1,058,807.

Specification of Letters Patent.

Patented Apr. 15, 1913.

Application filed July 17, 1911. Serial No. 638,960.

To all whom it may concern:

Be it known that I, FRANK B. TAFF, citizen of the United States, residing at Whitestone Landing, in the county of Queens and 5 State of New York, have invented certain new and useful Improvements in Propelling Mechanism, of which the following is a specification.

This invention relates to an improvement 10 in propelling mechanism for vessels and especially for the type of launches and similar boats.

More particularly my invention relates to a novel means for operating that type of 15 propeller blade which has a fish tail or fin construction as shown and described in Letters Patent granted to me, Patent Number 510,725 of December 12, 1893, wherein I have disclosed a type of propeller new to the 20 art. This type of propeller, as used to propel vessels, possesses many advantages over the paddle construction of propeller; according to arrangements which I provide the propeller blades are adapted to be reciprocated instead of being rotated as has been the usual practice. In my said patent, above 25 mentioned, it has been shown that hitherto many classes of propeller blades existed which provided for the use of a substantially 30 fin shaped propeller blade, but on account of the backward drag of the fin shaped propeller blade, due to imperfections in the mode of operating same, the use of such blades has fallen into desuetude.

35 This invention is an improvement over the novel mechanism shown in my aforementioned patent and comprises a novel form of propeller blade and a distinct means for operating same.

40 One of the objects of my present invention consists in giving to the fish tail or fin shaped propeller blade, a graded flexure which I have found to be very essential for the purpose of driving the vessel in a steady 45 course where the blades are not each used as a propelling means. I have found through continual practice that the very best results can be obtained by grading the flexure of the movable body of my type of blade 50 because the action of the waves is apt, at times, to impel an edgewise thrust against the sides of the blade and the torsion exerted will be greatest at or near the embedded end of the blade.

55 The preferred type of my invention consists in providing mechanism for reciprocating

the propeller blades simultaneously which is subject at all times to control from the operator, and to this end, I provide means for throwing either or both of the 60 propeller shafts out of operation.

The combined effect of the novel form of propeller blade disclosed and also of the novel actuating means therefor is to place under complete control of the operator the 65 various working parts which coöperate to move the vessel in a guided course.

With these and other objects in view, my invention consists in the arrangement, disposition and embodiment of the various 70 structural elements shown in the drawings and more particularly pointed out in the appended claims.

In the drawings, Figure 1 is a side view of a launch or other vessel taken at the stern, 75 and showing the inner arrangement of the novel propeller blade hereinafter described, Fig. 2 is a transverse section of the launch taken on the line X—X of Fig. 1 and showing the actuating mechanism for the propeller blades, Fig. 3 is a detail partly in section showing the loose bearings for the propeller shaft. Fig. 4 is a diagrammatic view of the propeller blade in action, Fig. 5 is a plan view of the mechanism employed for 80 throwing either or both of the propeller shafts out of operation, Fig. 6 is a detail in elevation of one of the actuating pinions and the means employed for throwing it out of operation, Fig. 7 is a vertical section of a 85 propeller blade looking at it from one end or taken from one end showing the arrangement of the overlapping laminations and the reinforcing members therefor.

In the drawings like reference characters 95 refer to similar parts wherever used.

In the drawings 1 designates a vessel of any kind and the one shown in the drawings is a launch. In this vessel I show at each side horizontally disposed guides 2 100 slightly above the keel which receives the propeller shafts 3, one at each side of the vessel and each projecting into the water; the arrangement therefore provides for guiding each propeller shaft in a horizontal 105 plane. Each propeller shaft is provided at one end 3^a with an integral socket piece 3^b which works in the socket bearing 4 hereafter described and the object of which is to mount a shaft loosely in its bearings.

At 6 is shown a novel form of propeller blade which has a graded flexure. Lamina-

tions are placed in overlapping series upon each other to give this graded flexion and the arrangement is effective to increase the springiness of the blade when in motion. 5 These laminations are each reduced in size in the ratio of their distance from the embedded end of the blade, each lamination overlapping the other outstanding laminations.

10 Reference being had to Fig. 7, it will be seen that 6^a is one of the laminations which from its position may be considered the main one of the series, since the inner laminations 6^{a'} bears upon its face; similarly another lamination 6^{a''} is shown overlapping the lamination 6^{a'}, and still another lamination, being the innermost one 6^{a'''} bears against each face of the lamination 6^{a''}. The main lamination 6^a is the outermost one 15 and has free thin edges. It is obvious, therefore through this arrangement that a graded flexure is given to the blades and that of the laminations the outermost is thinnest, the others thicker according to their distance 20 from the blade.

25 Any suitable means may be employed to mount the propeller blade on the shaft and at right angles thereto so as to be parallel to the longitudinal axis of the vessel, the 30 means I show comprising a two lobed shank 7 shown clearly in Fig. 7, which at one end is provided with an aperture to receive said shaft and a screw is tapped into the wall of the aperture and serves to fasten the blade 35 to the shaft in the conventional way. The object of the two lobed formation upon the shank is to provide weight at the innermost end, which weights have been found in practice to be very essential as will be herein- 40 after explained, to incline the blade in a substantially horizontal position when the propeller shaft is reciprocated to give the backward action of the fin shaped blade hereinafter described. The blade is adapted 45 to move between the inner sides of the two ears or lobes of the shank when in action.

50 In order to maintain each of the laminations in its proper place I form integral flexible ribs or reinforcing strips 7^a upon the shank and cause them to extend preferably in a radial direction; these ribs 7^a are fastened to all of the lamination at both 55 sides of the blade by any suitable means such as wire eyelets 7^b fastened to either or both of them as shown in the drawings.

60 From the above it will be noticed that the means for securing the propeller blade upon the shaft consists of a single piece member having lobed portions 7 and the integral radially extending rib members 7^a thereby causing the said bed to lie more securely 65 embedded within said means, I have designated said means as a shank but any other allied term may be used with the same

effect. It will also be noticed that the reinforcing ribs 7^a are flexible and move with the laminations and are loose and movable in the eyelet 7^b. Owing to the advantage of employing these fin shaped propeller 70 blades for marine propulsion they are mounted on the shaft in a novel way. Briefly, each propeller blade is set parallel to the longitudinal axis of the vessel so that the blades when in action will offer the least 75 resistance to the waves. The use of these fin shaped blades has been described in my above mentioned patent as will be noticed by those skilled in the art. It has been found however that the free motion of the 80 propeller blades has been unnecessarily retarded on several occasions by the rising and falling action of the waves and by reason of the fact that the means disclosed in my 85 patent has not embraced any means for allowing the propeller blades to slightly tilt below the waves when the action of reciprocation takes place.

90 In order that the inner propeller blade of the fin shaped construction shall not be impelled out of the water to which its tilting action may give rise the two ears or lobes 7 of the shank act as weights which will normally maintain the propeller blades 95 in their proper position.

95 The arrangement by which the propeller blades may be tilted is shown in Fig. 3, wherein 4 designates a socket bearing one end of which works loosely and freely in the socket piece 3^a of the propeller shaft and the opposite end is screwthreaded to receive the screwthreaded portion of the connecting piece 5 coöperating with the actuating means for the shaft 3. By this construction the undue rising action of the waves 100 will be effective only to slightly flex the propeller blades but will not cause either of them to become dislodged from its position in the water. Any suitable means may be employed to pack the guides 2 against leakage. 105 Instead of the lobes any other similar construction subserving the same end may be used but it must be borne in mind that the arrangement shown simplifies the construction by enabling the flexible laminations of each blade to have movement between the inner sides of each lobe. 110

115 The actuating means which I provide for reciprocating simultaneously each propeller shaft 3 is mounted on a platform 8 just above the keel of the vessel. Standards 9 rest above this platform, one at each side, and rotatably mounted above the standards is a spur wheel 10 and 11. Each of these spur wheels 10 and 11 carries a pitman 12 and 13 secured to rotate therewith by a wrist pin, as it is known to those skilled in the art. The free end of each pitman is connected to the connecting piece 5 which is shown held 125 in the socket bearing 4. The transmission 130

gear for each of these spur wheels comprises a main spur wheel 14 and a separate pinion 15 and 16 is driven by means of these spur wheels and has the customary driving connections with the spur wheels 10 and 11 respectively. A motor or any other agency may be employed to give rotation to the main spur wheel 14 and when in action the main spur wheel will impart motion to the other spur wheels 10 and 11 and will thereby actuate each pitman 12 and 13 to reciprocate each propeller shaft 3 in its guides 2. The said guides 2 are provided with a suitable packing embracing the propeller shaft as known in the art. Each of the propeller shafts 3, will through their number of driving wheels shown be impelled in a similar direction with respect to the sides of the vessel going inward or outward at the same time, thereby giving rise to the backward action of each propeller blade made clear in the diagrammatic view in Fig. 4. As shown in Fig. 4, the propeller shaft holds the propeller blade 6 in a plane at right angles thereto, which same propeller blade is shown in the figures to occupy a position parallel to the longitudinal axis of the vessel. When the propeller shaft 3 is reached outward as shown in dotted lines in Fig. 4, the line of flexure will be as shown in dotted lines A due to the opposition of the water currents and when it is moved from its outermost position, as shown, back to its innermost position, the line of flexure will be as indicated by dotted lines B, so that the resultant of the oppositely curved lines of flexure will be a center line between its normal position and its outermost position when the reciprocating means is in action. Owing to this action of the fin shaped propeller blades the action of the blades will resemble that of an ordinary fish and the vessel propelled thereby given speed and steadiness of course as has been demonstrated in actual use.

In order that the operator may throw either or both of the propeller shafts 3 out of operation and thereby cause one of the propeller blades to engage the water at a single movement, I provide a foot actuating device for a controlling means for reciprocating the propeller shaft. This is shown in Fig. 5 and to this reference will now be made. As the pinions 15 and 16 are the controlling members of the gearing before described in practice it has been found convenient to cause a treadle device to coöperate therewith but any other means may be provided for the same purpose that will enable the operator at will to render either or both of said shafts inoperative in whatever position placed. The pinions 15 and 16 are mounted loosely in sleeves 17 and 18 and when in service are pivotally mounted in standards 19 and 20 to hold the sleeves 17 and 18 in

actual alinement with respect to the shafts 10^b 11^b on the spur wheels 10 and 11; so that the pinions may operate said spur wheels, I provide a treadle or foot device 23 and 24 respectively for each pinion, the foot device comprising two integral parts pivoted at 24, and upon one of the members 23^a the foot of the operator is adapted to rest in order to throw the pinion out of gear and the other member 23^b normally bears upon the sleeve 17 or 18 as the case may be to hold it in position so that the pinions may engage the spur wheels for the purpose mentioned.

At 25 and 26 are shown any suitable yielding treadle device adapted to hold the foot device 23 and 24 in a normal position when it is desired to place the pinions in operation. The member 23^a, as shown, is flanged, so that the step 25 will engage the free action end of the member 23 until the operator causes it to be ejected from position and thereby causes the weight of the pinion 15 or 16 as the case may be, to force the end 23^b downward as shown in the dotted lines in Fig. 6, whereupon the pinions will be thrown out of gear. A similar device is shown operating in connection with the pinion 15 and needs no further description.

At 10^a and 11^a are shown suitable standards upon which wheels 10 and 11 are mounted. From this arrangement it will be obvious that the operator will have each of the propeller shafts completely under control at will enabling him to throw either or both of the shafts out of operation, a feature which gives added advantage to the propeller blades which are now given a graded flexure. The transmission gear 14 may be under control to operate either or both of the spur wheels 10 or 11 according to the operator's wish.

From the above description it is believed that the invention is clear and that by reason of the graded flexure of each propeller blade that enables it to better coöperate with the wave motion to propel the ship and also by reason of the independently actuated propeller shafts, the vessel may be more effectively driven in a set course and the equilibrium of the keel more steadily maintained.

I claim and desire to secure by Letters Patent:—

1. A device as described comprising a series of graduated blades bound fixedly connected at their inner ends and movably connected at their outer ends, and ribs movably secured to said outer ends.

2. A device as described comprising a series of graduated blades bound fixedly connected at their inner ends and movably connected at their outer ends, ribs movably secured to said outer ends, said ribs being radially disposed.

3. A fin shaped propeller consisting of a

- series of flexible blades having large and small ends each of which are fixedly connected together at the small ends and movably bound together at the large ends, said 5 blades being of varying graduations from the centermost thereof outwardly, the binding means consisting of flexible arms fixed outwardly to said blades, loops on said blades through which said arms project.
- 10 4. A fin shaped propeller consisting of a series of flexible blades having large and small ends each of which are fixedly connected together at the small ends and movably bound together at the large ends, said 15 blades being of varying graduations from the centermost thereof outwardly, the binding means consisting of flexible arms fixed outwardly to said blades, loops on said blades through which said arms project, retaining 20 members between which said blades are movable.
5. A fin shaped propeller consisting of a series of flexible blades having large and small ends each of which are fixedly connected together at the small ends and movably bound together at the large ends, said 25 blades being of varying graduations from the centermost thereof outwardly, the binding means consisting of flexible arms fixed outwardly to said blades, loops on said 30 blades through which said arms project, retaining members between which said blades are movable, said members having arcuate inner edges whereby the flexing movement of said blades is limited.
- 35 6. A fin shaped propeller consisting of a series of flexible blades having large and small end of each of which are fixedly connected together at the small ends and movably bound together at the large ends, said 40 blades being of varying graduations from the centermost thereof outwardly, the binding means consisting of flexible arms fixed outwardly to said blades, loops on said
- blades through which said arms project, retaining members between which said blades are movable, said members having arcuate inner edges whereby the flexing movement of said blades is limited, means for reciprocating said propeller. 45
7. A fin shaped propeller consisting of a series of flexible blades having large and small ends each of which are fixedly connected together at the small ends and movably bound together at the large ends, said 50 blades being of varying graduations from the centermost thereof outwardly, the binding means consisting of flexible arms fixed outwardly to said blades, loops on said blades through which said arms project, retaining members between which said blades are movable, said members having arcuate inner edges whereby the flexing movement of said blades is limited, means for reciprocating said propeller horizontally. 55
8. A fin shaped propeller consisting of a series of flexible blades having large and small ends each of which are fixedly connected together at the small ends and movably bound together at the large ends, said 60 blades being of varying graduations from the centermost thereof outwardly, the binding means consisting of flexible arms fixed outwardly to said blades, loops on said blades through which said arms project, retaining members between which said blades are movable, said members having arcuate inner edges whereby the flexing movement of said blades is limited, means for reciprocating said propeller horizontally, and means 65 for tilted.
- In testimony whereof I affix my signature in presence of two witnesses.

FRANK B. TAFF.
